UNITED STATES PATENT OFFICE.

JOSEPH W. HORTON, OF BLOOMFIELD, NEW JERSEY, ASSIGNOR TO WESTERN ELECTRIC COMPANY, INCORPORATED, OF NEW YORK, N. Y., A CORPORATION OF NEW YORK.

SECRET COMMUNICATION.

Application filed July 2, 1923. Serial No. 648,903.

The present invention relates to method and means for the transmission of messages with secrecy. The invention is based on the principle that the intelligibility of received waves depends upon the reception of a certain series of frequency components occurring in quite a definite order between definite limits, with certain relative amplitudes, and to the practical exclusion of other frequency components. The degree of intelligibility may be reduced by disturbing the order of frequency of the components, or by changing the frequency limits or by deleting some of the frequency components or varying their amplitudes or by introducing extraneous or "noise" components. If the noise components are within the range of essential signaling frequencies so as to be incapable of separation from these frequencies by filtering and if they are of large amplitude, or if a material displacement in absolute frequency occurs in the components that are received, even though no essential signal components be deleted, the received waves may readily be made impossible of understanding as received, and also extremely difficult to decipher by any apparatus, in the absence of knowledge of the scheme by which the wave is built up.

The invention is particularly applicable to systems in which the signal is transmitted as a modification of a high frequency inaudible wave which must be detected to enable the signal to be heard. In the detecting process a number of frequency components are produced by combination of frequency components present in the high frequency wave. By properly choosing and introducing confusion components into the high frequency wave, it is possible to predetermine the audible components resulting from detection and to make them of such frequency and amplitude that it is a matter of great difficulty, amounting to practical impossibility, for an unauthorized person to unravel the detected and unintelligible audible wave.

The process of detection of a signal-modified high frequency wave to give the signal depends upon the interaction between the variation components of the high frequency wave, which variations arise from the control of the carrier wave by the signal, and the non-variation or unmodulated high fre-

quency wave component. In the usual signal-modified wave the relation between the components is such that upon detection of the wave, components occupying the normal signal frequency range are produced. This is so by the very nature of the case, since the components existing in a signal-modified wave are themselves determined by the process of modulation of the unmodulated high frequency wave by the signal so that the detecting process may be looked upon as a reversal of this modulating process, whereby the reproduced signal is in exact correspondence with the original signal.

The invention takes advantage of the necessity for a proper frequency relation to exist between components of a received wave if the detected wave is to correspond with the original signal, and one manner of taking advantage of this is by introducing into the modulated wave such components as will prevent correspondence between the detected components and the original signal.

One of the objects of the invention, therefore, is so to alter the transmitted signal-modified wave that the components resulting from detection lack correspondence with the signal, to an extent amounting to unintelligibility.

An auxiliary object is to introduce confusion or noise components into the transmitted wave, so that, apart from or together with the lack of correspondence between the original signal and the reproduced components, additional components of large amplitude are produced, which tend to confuse and drown out any otherwise understandable components.

According to one feature of the invention a single frequency component, different from the high frequency component or carrier that is modulated, is introduced into the transmitted wave. This component may be termed a "false carrier" since upon detection it causes the production of components shifted in frequency from the frequencies occupied by the components normally produced by interaction with the true carrier.

In accordance with another feature of the invention the true carrier component of the transmitted wave is suppressed and one or more false carriers are introduced into the transmitted wave.

According to another feature, the false

carrier or false carriers is or are shifted in frequency from time to time to render the discovery of the false carrier frequency more difficult.

5 Other features of the invention comprise method and means by which the introduction of the false carrier or, in general, of the confusion components, is controlled at a transmitting point, and the effects of such components in effacing or masking the intelligibility of the received waves is neutralized at the point at which the signal is authorized to be received in intelligible form.

10 Briefly and specifically stated, the invention involves the introduction at a transmitting point of one or more false carriers or confusion components, and at a receiving point the neutralization of the deleterious effects of such introduced components upon the intelligibility of the received components. This neutralization may be carried out under control of the false carriers themselves. The received wave is detected and one of the components resulting by detection from the false carrier component is used as a base frequency from which may be built up components identical with the true carrier and the one or more false carriers, respectively. The components so built up are used to reproduce the signal and to neutralize the effects in the reproduced signal of the received false carrier or confusion components.

15 The various objects and features of the invention and its exact nature and operation will be made clear from the following detailed description in connection with the accompanying drawing.

20 In the drawing, Figs. 1 to 6 show diagrams illustrative of the frequency relations involved in the system of the invention; Figs. 7 and 8 are schematic circuit representations, respectively, of a transmitting station and a receiving station according to the invention; and Figs. 9 and 10 show alternative transmitting and receiving circuits, respectively.

25 The usual carrier or radio-frequency wave modulated by speech, noise, or other sound waves, is known to comprise in general a frequency corresponding to the unmodulated frequency of the carrier wave itself and two side bands of frequencies each equal in width to the actual width of the band of frequencies making up the sound waves, one of these side bands extending into the frequency range higher than the carrier frequency and the other side band extending into the range lower than the carrier frequency. Thus in Fig. 1 c represents the carrier frequency, and the horizontal arrows represent the extent either side of the carrier frequency to which the side bands reach. The side bands are indicated as being of width s , this referring to the frequency range utilized in

speech transmission. The absolute frequencies comprised in a speech modulated wave may, therefore, be designated c , $c+s$, and $c-s$. When such a wave is detected the sum frequencies $2c$, $2c+s$, $2c-s$, and also double frequencies result as the higher components due to the square law action of the detector, these frequencies being ordinarily above audibility, and the difference-frequencies s and $2s$ result as the low or audible-frequency components from the same action of the detector. Many other frequency components may result but are of no practical concern in the usual type of signaling system. The frequencies $2s$ are ordinarily of very small amplitude relative to the frequencies s , so that for practical purposes it may be considered that only the band s is received.

30 According to the invention one or more frequency components is or are introduced into the modulated wave in such a way as to render it incapable of being received and understood by the types of receiving circuit generally known or used. In Fig. 1 for example, the unmodulated carrier component c of the wave to be transmitted is preferably suppressed, this being indicated by the use of a dotted line in the drawing, and two frequencies situated at the frequency intervals f_A and f_B , respectively, from the carrier frequency are introduced into the respective upper and lower side bands. When two of these introduced frequencies or false carriers are used, they are preferably positioned unsymmetrically with respect to the carrier frequency and may lie in the two speech side bands or outside the frequency limits of these side bands. The component situated at the interval f_A , for example, is shown nearer to the frequency of the unmodulated carrier c than is the component situated at the interval f_B . The frequency components of such a wave may, therefore, be represented as $c+s$, $c-s$, $c+f_A$ and $c-f_B$, the carrier component c being assumed, as stated, to have been suppressed.

35 The principal frequency components resulting from the simple or non-heterodyne detection of such a wave are diagrammatically shown in Fig. 2. The sum-frequencies are all higher than the carrier so that these components as well as the double frequency components will ordinarily be inaudible and need not be considered. The difference-frequency components are seen to be:

$$f_A-s, f_B-s, f_A+s, f_B+s, f_A+f_B$$

40 and a range of components resulting from the interaction in the detector of every speech component in the $c+s$ side band with every speech component in the $c-s$ side band. These latter components might at first sight be thought to represent the double frequencies of speech, but while the double frequency component of each speech compo-

5 nent is theoretically present, a large number of other components are also present which do not represent speech but are merely noise components impressed upon the double-frequency components. The components resulting from the interaction of the two speech side bands by themselves, may therefore be disregarded. It is furthermore to be noted that these components are of very 10 low amplitude compared with the components produced as a result of introducing the false carriers as will presently be described, and that these stronger components completely drown out the weak double frequency 15 components of speech.

The components—

$$f_A - s, f_B - s, f_A + s, f_B + s, \text{ and } f_A + f_B$$

20 may be interpreted as representing, respectively, four side bands based on f_A and f_B , each of which (except for any doubling back of a band upon itself or overlapping of one portion upon another, as explained herein-after) may be considered to be of the width 25 s or of the width of the normal speech band, and the single component representing the sum of the two frequencies f_A and f_B . In the diagram of Fig. 2 these components are represented at convenient distances above 30 the horizontal axis, their numerical frequency values being determined from their position in the horizontal direction. No attempt is here made to indicate their relative amplitudes. Two side bands of speech 35 width extend in the positive direction from the respective components f_A and f_B , these bands being $f_A + s$ and $f_B + s$, respectively.

40 The side band $f_A - s$ and $f_B - s$, may be interpreted as being, in part, simply speech bands displaced in the downward direction in the frequency scale by the amount f_A or f_B as the case may be, and as being, in part, inverted in their frequency orders in that portion of the normal speech range extending 45 from zero to f_A or f_B , respectively, the inverted portion being, therefore, superposed on the displaced portion. These partly inverted and partly displaced side bands may 50 therefore be considered as doubled back upon themselves. The component $f_A + f_B$ represents a single-pitched tone and for the 55 frequencies of f_A and f_B assumed, this tone lies within the normal speech frequency limits.

60 No one of these resulting audio-frequency components is capable of producing understandable speech. The double-frequencies come, perhaps, the nearest to being capable of being understood but, as pointed out above, these are intermixed with a large number of noise components and are of such small amplitude that they are drowned out by the other components. It is known that shifting normal speech as a whole upward or 65 downward in the frequency spectrum by

even a very slight constant amount introduces very serious distortion and a material frequency shift renders it incapable of being understood. However, it will be noted that in addition to the incapability of any single one of these bands to reproduce speech, the frequencies may easily be so chosen (as is indicated) that each band overlaps the others in the occupied frequency range so that a still greater confusion results from the practical impossibility of distinguishing one band from another either by ear or by any usual apparatus such as filters.

70 If it be attempted to receive the waves of the character shown in Fig. 1 by the heterodyne method or by the homodyne method, sometimes referred to as zero beat reception because the locally introduced oscillations are of the same frequency as the carrier component, the same kind of difficulties are 75 encountered as described in the case of simple detection. The use of a local wave materially different in frequency from the received frequencies will result in even more 80 confused components than are indicated in Fig. 2 since the audible beats produced between the heterodyne wave and the received components simply serve to add more of the 85 components of equally meaningless character. It is improbable that one would locate the exact frequency of the unmodulated carrier and adjust the local oscillator to that frequency. If this be done however, the inverted and displaced speech bands due to 90 the false carriers are present as indicated in Fig. 2 and two noise components of frequencies f_A and f_B are now superposed on the speech bands and cannot be separated from the speech by any ordinary methods. If 95 the amplitude of the locally supplied wave is increased in an attempt to make the speech louder, this results in making the noise components louder, and moreover, the 100 false carrier components may purposely 105 be made of much higher amplitude than the speech side band components in the wave that is sent out, so that a complete masking of the speech results. The likelihood of locating the exact carrier frequency 110 is lessened by the fact that f_A and f_B are located unsymmetrically with respect thereto. An observer in exploring the 115 frequencies of the wave would not be inclined to choose a beating frequency which gave 120 audible tones in place of one corresponding to a beating frequency half way between $c + f_A$ and $c - f_B$, and such a beating frequency would give effects somewhat similar to those of Fig. 2 where two of the side bands 125 are partly inverted. If the local oscillator were set at either frequency $c + f_A$ or $c - f_B$ only displaced bands, incapable of being understood, would be received.

130 Reference will now be had to Figs. 7 and

8, which show, respectively, a transmitting station and a receiving station for carrying out secret speech transmission according to the invention. These stations are represented as being associated with antennae for communicating by radio waves, but it will be obvious that they might equally well be associated with a transmission line of any desired type.

- 10 The oscillator OS may be of any suitable type and is indicated as comprising an electric discharge device provided with a feed back coupling and a frequency-determining circuit in accordance with usual practice.
- 15 An oscillator suitable for this purpose is disclosed in United States patent to Hartley No. 1,356,763, October 26, 1920. The harmonic generator HG₁ may be of the type described in the U. S. patent to Kendall No. 20 1,446,752, February 27, 1923. As specifically shown in the present system, it is provided with a high resistance in the grid circuit for promoting the production of harmonics. The wave from the source OS is impressed 25 on the circuit HG₁ with such amplitude as to produce a distorted wave in the output circuit of the harmonic generator, the wave shape being such that the wave is rich in harmonics. The other harmonic generators 30 indicated throughout the system, such as HG₂, HG₃, etc., may each be similar in construction and operation to HG₁ and to the disclosure of the Kendall patent.

Various filters F₁, F₂, etc., are indicated 35 at various parts of the system for selectively transmitting a wave of a particular frequency or range of frequencies and for suppressing transmission of waves of other frequencies. Each of these filters may be constructed and proportioned in accordance 40 with the disclosure in U. S. patent to Campbell No. 1,227,113, May 22, 1917.

Balanced modulators BM₁, BM₂, etc., are used for producing modulation of one wave 45 in accordance with another, and for suppressing transmission of the unmodulated component. These modulators may be of the general type disclosed in U. S. patent to Carson No. 1,343,306, June 15, 1920, or in 50 U. S. patent to Hartley No. 1,419,562, June 13, 1922.

The detectors or demodulators D₁, D₂ (Fig. 8) are of the usual three-element discharge type, and the modulator M is of 55 similar construction, the purpose of both these detectors and this modulator being to produce sum and difference frequency components of the impressed wave-components. A modulating circuit of this type is disclosed in U. S. patent to Van der Bijl No. 1,350,752, August 24, 1920.

The description from this point on, will be simplified by reference to particular frequency values, and these values are indicated

on the drawing. It is to be understood, 65 however, that these values are only for illustrative purposes and to serve as examples, but that any other suitable frequencies may be chosen and ordinarily would be chosen if two of the systems of the invention were in 70 operation side by side or if the invention were applied to wire rather than to radio transmission.

Referring now to the operation of the system shown in Figs. 7 and 8: The oscillator OS generates a continuous wave of a frequency which for convenience will be assumed to be 100 cycles per second, and this wave is impressed on the harmonic generator HG₁ with such amplitude as to overload the harmonic generating tube and produce a highly distorted wave in its output. This harmonic generator operates, in the manner disclosed in the Kendall patent referred to, to produce a number of harmonic 80 frequencies of the impressed wave, and the construction and operation may be such that all of the harmonics from the double frequency of the impressed wave up to harmonics higher than the 10th harmonic are 90 produced. These harmonics may be filtered out from the output circuit of the harmonic generator for separate use as may be desired. The filter F₁, which may be a band filter having a narrow transmission range 95 or may be simply a sharply tuned circuit, is designed to select the frequency 1000 and impress it upon the harmonic generator HG₂, sufficient amplification being introduced if necessary so that the harmonic generator HG₂ is overloaded and produces a highly distorted wave in its output. The filter F₂ selects the harmonic frequency 10,000 which is supplied to the neutral branch of each of the balanced modulators 100 BM₁ and BM₂. This central or neutral branch is so related to the output windings in the case of each of these modulators that 105 none of the waves supplied to this branch is repeated into the output circuit of the modulator except when a modulating or control wave is supplied to the control elements of the modulator in such a way as to disturb the balance. When such control waves are impressed, the wave impressed on 110 the neutral branch is transmitted with an amplitude proportional to that of the control waves and the resulting modulated wave is resolvable into two side bands having frequencies higher and lower respectively than the impressed 10,000 cycle wave but containing no component of the 10,000 cycle frequency. This action is more fully described 115 in the Carson patent above referred to.

The filter F₄ selects from the output of the harmonic generator HG₁ the wave of frequency 600, which is applied to a control winding of the balanced modulator

BM₁. Similarly, the filter F₅ selects the frequency 1100 and applies it to the balanced modulator BM₂.

The speech to be transmitted is directed 5 against the microphone 5 and the resulting speech currents are supplied through the amplifiers A₁ and A₂ to control windings of the respective modulators BM₁ and BM₂. The effect of the waves applied to the modulator BM₁ is to produce two side bands of 10,000 cycle wave, these side bands being made up of frequencies corresponding to the impressed speech and each containing a single frequency component spaced in frequency 15 600 cycles from the center of the wave, which would be occupied by the 10,000 cycle component if this were not suppressed. Similarly the modulator BM₂ produces two side bands of the 10,000 cycle waves, these 20 side bands representing speech components with a single frequency introduced into each side band at an interval of 1100 cycles from the 10,000 cycle frequency. Suitable amplification may be introduced with the filters 25 F₄ and F₅ so that the single frequency components corresponding to the 600 cycle and 1100 cycle point in the side bands respectively are of relatively large amplitude compared with the speech side band amplitudes. 30 The character of the wave produced by the modulator BM₁ is indicated in Fig. 3. Here the 10,000 cycle component is indicated by a dotted line signifying that this component is suppressed. The modulated wave is 35 made up of the two side bands indicated as extending approximately from the 10,000 cycle position to the 12,500 cycle and the 7,500 cycle limits respectively. At intervals 40 600 cycles from the 10,000 cycle point in each direction the respective single frequency components of relatively large amplitude are located. Fig. 4 in similar manner indicates the composition of the wave in the output of the modulator BM₂, this wave 45 differing from that produced by the modulator BM₁ in the different position occupied by the single frequency component or false carrier.

The filter F₆ is proportioned in the manner indicated in the Campbell patent, referred to, to selectively transmit the lower side band produced by the modulator BM₁, but to suppress transmission of the upper side band, that is, this filter transmits only 55 that portion of the wave indicated in Fig. 3 which lies to the left of the 10,000 cycle frequency. Conversely, the filter F₇ transmits only the upper side band of the wave produced by the balanced modulator BM₂, that is, only that portion of the wave in 60 Fig. 4 which lies to the right of the 10,000 cycle line. The waves selectively transmitted by these filters are impressed on the control circuits of the radio transmitting modulator BM₃. The character of the re-

sultant wave supplied from these two filters to the modulator BM₃ is indicated in Fig. 5 and is seen to consist of two speech side bands of the 10,000 cycle wave, the upper side band containing a noise component 70 situated 1100 cycles higher than the 10,000 frequency and the lower side band containing a noise component situated 600 cycles lower than the 10,000 frequency. The neutral branch of this modulator is supplied 75 with a 100,000 cycle wave produced in the harmonic generator HG₃ and selected by the filter F₈. Suitable amplification may be introduced into any of the waves supplied to the modulator BM₃ as may be desired. 80

The modulator BM₃ operates in a manner similar to that described of the other balanced modulators to produce two side bands resulting from modulation of the 100,000 cycle wave by the waves from the filters F₆ 85 and F₇. The character of the lower side band resulting from this modulation is indicated in Fig. 6. This wave is seen to have the same frequency arrangement as the wave indicated in Fig. 5, except that the frequency 90 order of the components is inverted and the inverted wave, as a whole, is shifted in the absolute frequency range to such position that the center of the wave is at 90,000 cycles rather than at 10,000 cycles. An upper side 95 band with its center at the frequency 110,000 is also produced but the transmitting antenna 6 is preferably quite sharply tuned so as to radiate only the lower side band and to suppress practically completely the upper 100 side band.

It will be noted that the composition of the wave in Fig. 6 which is the wave actually transmitted from the antenna 6, is of the same character as that indicated in Fig. 1, 105 where C is now 90,000 cycles, f_A is 600 cycles and f_B is 1100 cycles. If this wave as transmitted were detected by the ordinary methods, either simple detection or detection by the aid of locally supplied waves, no components representing speech would result but only the confusing components above described in connection with Figs. 1 and 2 would be obtained.

The wave transmitted from the antenna 6 115 is received at the station indicated in Fig. 8 upon the receiving antenna 7. Detection of this wave by the detector D₁ will produce as one component the f_A+f_B component, or in this case 1700 cycles. This component is 120 selected by the filter F₉ and after suitable amplification, if desired, is impressed on the modulator M, which, together with the filter F₉, the harmonic generator HG₄ and the filter F₁₀, forms a sub-multiple frequency 125 generator of the type described in my application Serial No. 545,562, filed March 21, 1922. The principle of operation of this circuit may be described briefly as that of a generator in which the feed-back from the 130

output side to the input side contains frequency converting means. It is evident that, with the proper character of selective circuits and with sufficient amplification, such a circuit may be made to oscillate continuously under the control of impressed waves, since an initial impulse produced by shock excitation or otherwise in the filter F_9 and of a frequency of 100 cycles will excite the harmonic generator HG_4 to produce harmonic components, the sixteenth multiple of which is applied through the filter F_{10} to the input circuit of the modulator M where it combines with the incoming frequency of 1700 to produce the difference frequency of 100, this being in turn supplied to the harmonic generator HG_4 and causing the action to continue.

The result of the action of the sub-multiple frequency generating circuit causes the harmonic generator HG_4 to produce a number of components of the impressed 100 cycle wave under control of the received 1700 frequency wave. The filter F_{11} selects the 1000 frequency wave and applies it to the harmonic generator HG_5 , from the output of which the filter F_{14} selects the 10,000 cycle wave which is supplied to the neutral branches of the respective balanced modulators BM_4 and BM_5 . The filter F_{12} selects the 600 cycle component from the harmonic generator HG_4 and supplies it to the control windings of modulator BM_4 , and the filter F_{13} selects the 1100 cycle component and similarly supplies it to the control windings of modulator BM_5 .

The action of the modulator BM_4 is to produce two side frequencies of 600 cycles above and below the 10,000 frequency respectively and having therefore the respective frequencies 10,600 and 9,400. The filter F_{16} selects for transmission only the 9,400 component, this being supplied to the circuit generally indicated by the numeral 9, the purpose of which circuit is to adjust the phase of the 9,400 cycle component in a manner to be described. The modulator BM_5 produces two side frequencies of 8,900 cycles and 11,100 cycles respectively, the upper one of which is selectively transmitted by the filter F_{17} to the phase controlling circuit 10.

Some of the 10,000 cycle wave from the filter F_{14} is supplied with suitable amplification to the harmonic generator HG_6 from the output of which the filter F_{15} selects the 100,000 cycle component. This 100,000 frequency is introduced through the coupling 11 to the input circuit of the detector D_2 which is also coupled to the receiving antenna 7. As a result of the action of the detector D_2 , the sum and difference frequency components of the 100,000 cycle wave and the received wave are produced. The difference frequency components include a

wave of the character indicated in Fig. 5, this being clear from considering that each of the components of the wave indicated in Fig. 6 (which is the received wave) is subtracted from the locally supplied frequency 100,000. The filter F_{18} is designed to pass selectively the frequencies comprised in the difference frequency wave and this wave is thereafter impressed on the amplifying circuit A_3 .
75

The input circuit of the amplifier A_3 is also supplied with the 11,100 frequency component from the circuit 10 and with the 9,400 cycle component from the circuit 9. Suitable amplification or attenuation may be introduced into the several circuits associated with the input of the amplifier A_3 and also the phase of the locally supplied components may be so adjusted by means of the circuits 9 and 10 that the 9,400 cycle component and the 11,100 cycle component locally supplied are each of the same amplitude as the corresponding components impressed from the detector D_2 and are each in phase opposition to these respective components. As a result, the false carriers or noise or confusion components purposely introduced into waves at the transmitter are balanced out in the amplifier A_3 leaving only two speech side bands based on a 10,000 cycle wave. These side bands, after passing through the amplifier A_3 , are supplied to the control winding of the modulator BM_6 where they interact with the locally supplied 10,000 cycle component from the output of the filter F_{14} and produce speech currents in receiver R in the manner indicated in Carson's patent above referred to.
95

In the foregoing description, it is stated at several points that amplification may be introduced where desired. No attempt has been made to indicate all of the points where amplification may be desirable but it will be understood that amplifiers or attenuating networks, and potentiometers and the like for regulating the amplitude of the waves may be employed.
105

Under some circumstances, it may be desirable to render the secrecy scheme utilized still more incapable of being deciphered than the scheme employed in the system of Figs. 7 and 8. For example, it might be desirable under some conditions, where the general secrecy scheme made use of might be known, to employ some means for rendering it more difficult to discover the frequencies f_A and f_B or false carriers. One way of rendering false carrier frequencies more difficult of discovery would be to change their frequency from time to time during transmission. This method is applicable, of course, to systems in which two false carriers, such as are described in Figs. 7 and 8 are used or in systems where more than two false carriers or only one are used. If more
115
120
125
130

than one false carrier is used, the circuit arrangements for providing the false carriers and shifting their frequencies becomes somewhat involved, and for the sake of simplicity and for the purposes of illustration it has been deemed sufficient to show as an example of a system with variable frequency false carriers, the system indicated in Figs. 9 and 10 in which provision is made for using at any instant a single false carrier and for shifting the frequency of this false carrier from time to time. However, by mere extension of the principle illustrated in Figs. 9 and 10, to be described, it will be clear that the frequencies of a plurality of false carriers may likewise be shifted from time to time, in cases where a plurality of false carriers are used.

The frequency of the false carriers could obviously be shifted in accordance with any desired scheme. For example, the frequency might be shifted in accordance with a pre-arranged time schedule, the corresponding shifts being effected simultaneously at the transmitter and receiver with preferably some synchronizing system for controlling the shifting means at the two stations.

In the system of Figs. 9 and 10, however, the shifts in frequency of the false carrier waves are effective under control of the speech to be transmitted, the specific arrangement being such that during a pause of sufficient length between words a frequency shift is made simultaneously at both stations.

For the purpose of shifting the frequencies, step-by-step switches of the type commonly used in the automatic telephone art are indicated as being employed. In Fig. 9, for example, the rotatable switch arms 12 may be mounted upon a single shaft arranged for actuation under control of the stepping relay 14. Similarly, the brush arms 15 may be stepped by the relay 17. In Fig. 10, a number of pairs of brush arms 18 to 24 inclusive, are indicated together with a single stepping relay 25 for controlling all of these brushes. It will be obvious that all of the brushes 18 to 24 may be mounted on a single shaft or upon different shafts with suitable driving connections so that when relay 25 actuates its armature, all of these brushes are advanced from the contact upon which they are resting to the next succeeding contact in the direction indicated in each case by the arrow.

The stepping relays 14, 17 and 25 are each arranged in the manner common in the automatic telephone art to effect no movement in the brushes during the upward or attractive stroke of their armatures but to advance the brushes one step during the backward stroke of the armatures. This may conveniently be arranged, for example, by having the armatures normally retracted by a spring

and providing a pawl which upon the attracting stroke passes from engagement with one tooth of a ratchet wheel to engagement with a succeeding tooth and upon retraction of the armature moves the ratchet wheel one step.

The relays 14, 17 and 25 are normally de-energized except when speech is being transmitted. Speech currents directed against the microphone 26, for example, are repeated through amplifier 27 and set up corresponding speech currents in the winding 28. The grid of the rectifier tube 29 is normally at such a high negative value that the space current in the tube 29 is too low to cause energization of the relays 14 and 17, but the speech currents in the winding 28 producing corresponding voltage changes on the grid of the tube 29 and cause an increase in the space current in this tube to such a value as causes the relays 14 and 17 to attract their armatures. At the receiving station of Fig. 10, received speech currents are impressed on the rectifier 36 which acts in a manner similar to the rectifier 29 at the transmitting station to control relay 25, and this will be made more clear from the detailed description of the operation which follows.

It will be assumed that at the beginning of the operation to be described, each of the brushes in Figs. 9 and 10 is in the position indicated in the drawing, which will be termed position 1, signifying that each brush is in position to establish connection with the uppermost of the three stationary contacts respectively associated with it.

The oscillator OS in Fig. 9 and the harmonic generator HG₇ operate as described in connection with Fig. 7 to produce a series of waves having frequencies which are harmonics of the base wave of 100 cycle frequency. The filter F₂₃ selects 1000 cycle component and applies it to the harmonic generator HG₈, from the output of which the filter F₂₄ selects the 10,000 cycle component and applies it in turn to the harmonic generator HG₉, and from the output of HG₉ the 100,000 cycle component is selected by the filter F₂₅ to be used as the radio or carrier frequency. This component is applied to the neutral branch of the balancing modulator BM, associated with the transmitting antenna 30.

With the brushes 12 and 15 in position 1, the filter F₂₆ is connected between the harmonic generator HG₇ and the input side of the amplifier A₄ so that this amplifier is supplied with a 400 cycle component. As soon as speech is directed against the microphone 26, the amplified speech currents are supplied preferably through a second amplifier A₅ to the control windings of the balanced modulator BM, together with the 400 cycle component from the amplifier A₄, and two side bands of the 100,000 cycle wave are pro-

duced in the modulator, each of these comprising components representing speech and a 400 cycle noise component or false carrier, preferably of large amplitude compared with the speech components. These side bands are radiated from the antenna 30. With the beginning of the conversation, the relays 14 and 17 are energized in the manner previously described and are thereby put in readiness to advance the brushes 12 and 15 as soon as a sufficiently long pause occurs in the talking, thereby permitting these relays to release.

The side bands transmitted from the antenna 30, if detected on an ordinary detector, would produce only the double frequencies of speech upon which would be superposed a very strong component of 800 cycles. As stated above, it is practically impossible to understand the double frequencies of speech, and the relatively loud 800 cycle component would completely mask what little intelligibility the double frequencies have. If a local oscillator of the carrier frequency were used to receive the transmitted wave, a very loud noise current of a 400 cycle pitch would be superposed on the speech and render the received currents of practically zero intelligibility. By the use of two or more false carriers or noise components, particularly if they are unsymmetrically spaced as described in the case of Figs. 7 and 8, the wave would be rendered still more difficult of understanding.

The wave received on the antenna 31 of station 10 is detected in the circuit D_3 and produces a component of 800 cycles in the output. This component is selectively passed through the filter F_{26} , brush arms 18 and 19 being in position 1, and is impressed on the modulator M_2 . This modulator, together with filter F_{29} , harmonic generator HG_{10} and the particular filter F_{30} , F_{31} , F_{32} , that is connected in the circuit at any instant, forms a sub-multiple generator of the type described in connection with Fig. 8. With brush arms 20 and 21 in position 1 the application of the 800 cycle component to the modulator M_2 causes the production in the modulator of the difference frequency between the 800 cycle component and the 700 cycle component transmitted through the filter F_{26} so that a component of 100 cycles is maintained in the input circuit of the harmonic generator HG_{10} .

The filter F_{33} selects the 1000 frequency component from the output of the harmonic generator HG_{10} and applies this component to generator HG_{11} . The 10,000 cycle component occurring in the output of the harmonic generator HG_{11} is selectively transmitted by filter F_{34} to harmonic generator HG_{12} , from the output of which the 100,000 frequency component is applied through filter F_{35} to the input circuit of detector D_4 .

This detector serves to combine the received wave components with the locally supplied 100,000 cycle component to produce speech frequencies with the 400 cycle noise component superposed thereon, and the speech frequencies are selectively transmitted through the filter F_{36} to the input side of the amplifier 32.

With the brush arms 22 and 23 in position 1, the filter F_{37} is made operative to select the 400 cycle component in the output of harmonic generator HG_{10} and supply it through brush arm 24 in position 1 to the phase adjusting circuit 33 and transformer 34. Also the secondary of this transformer is connected through the uppermost brush arm 24 to the input circuit of the amplifier 32. The phase of this 400 cycle component is so adjusted by means of the circuit 33 that this component exactly neutralizes the 400 cycle noise component in the detected speech wave, and the speech in understandable form is transmitted through the amplifier 32 and speech transformer 35 to the receiver R.

When the conversation started, the speech currents present in the transformer 35 were impressed on the rectifier 36 which is controlled in a manner entirely analogous to that described in connection with rectifier 29, Fig. 9, and the resulting increase in space current energized relay 25 causing its armature to engage a tooth on the driving mechanism for the various brush arms indicated in Fig. 10 and to hold the armature attracted so long as no pause of less than predetermined length occurs in the conversation. When a pause of sufficient length occurs between words or sentences, for example, the rectified current in the rectifiers 29 and 36 respectively, falls to such a low value that the relays 14, 17 and 25 simultaneously release their armatures and advance the brush arms 12, 15 and 18 to 24 inclusive, to the second position, that is, the position succeeding that in which the brush arms are shown in the drawing, in the direction of the arrows. With the brushes in the second position, the conversation when it is resumed, proceeds exactly as described above except that the false carrier or noise frequency component has been shifted to a different frequency from what it formerly had. In the example chosen for illustration, the false carrier has a frequency 500 cycles different from the true carrier when the brushes are in position 2, that is, a 500 cycle tone is superposed on the detected speech.

This 500 cycle tone is impressed on the outgoing speech at the station in Fig. 9 in the modulator BM_7 and is derived by means of the filter F_{21} from the output of the harmonic generator HG_7 when brushes 12 and 15 are in position 2.

The frequency resulting from detection of this 500 cycle modulating component is now

of 1000 cycles and this component is selected from the detector D_3 by the filter F_{27} , brush arms 18 and 19 being in position 2. The submultiple frequency generator circuit continues to derive the base frequency of 100 cycles for supplying to harmonic generator HG_{10} through filter F_{29} since brush arms 20 and 21 are now in position 2 and filter F_{31} is in circuit to feed back the 900 cycle component to combine with the incoming 1000 cycle component. The 500 cycle tone in the received speech is neutralized by the 500 cycle tone selected by filter F_{38} from the output of harmonic generator HG_{10} and the phase of this neutralizing component is adjusted by means of the circuit 37, brush arms 24 being in the second position so that this neutralizing component is supplied to the amplifier 32. So long as the conversation continues without sufficient pause, relays 14, 17 and 25 remain with their driving pawls in engagement with the shafts of the respective brush arms. A pause of sufficient length occurring in a conversation with the circuit conditions as last described above causes all of the switch arms shown in Figs. 9 and 10 to advance to the third position, whereupon the false carrier or noise component is again shifted in frequency. In the example chosen for illustration, the new noise frequency is 600 cycles and it will be seen that brush arms 12 and 15 in position 3 connect the filter F_{22} in circuit to supply the 600 cycle component to the outgoing modulator. Also at the receiving station, filters F_{28} , F_{32} , F_{39} and phase adjusting circuit 38 are cut into the circuit so that when the talking is again resumed, the neutralizing component applied to the phase amplifier 32 is now 600 cycles and is of proper phase to neutralize the 600 cycle noise component of the received speech. When talking is resumed, relays 14, 17 and 25 are again energized in preparation for advancing the various brush arms into position 1 upon the occurrence of a sufficiently long pause.

It will be seen that the above described arrangements for shifting the frequency of the false carriers or noise components are such that no shift in frequency is made in the middle of a word or between words that follow each other with the normal rate of succession used in ordinary conversation. The relays 14, 17 and 25 may be made sufficiently slow so that a considerable pause is necessary before a shift in the frequency of the false carrier is made, such, for example, as the pause which occurs between sentences or during a considerable break in the conversation as between the time when one party ceases talking and the distant party begins to talk.

There are two possible ways in which the frequency shifting system might get out of step, that is, first, due to failure of the

brushes at the receiver to advance a step when the brushes at the transmitter advance, and second, due to an advance of the brushes at the receiver when no advance takes place at the transmitter. Since the stepping of the brushes at the receiver is effected upon release of the relay 25, and this relay is positively held energized by received energy, it is highly probable that the brushes at the receiver will always advance with an advance of the transmitter brushes, so that the first of the two conditions mentioned above may be considered as practically never existing. There may be interruptions in the transmission due to other causes than a pause in the conversation and lasting sufficiently long to permit relay 25 to release and advance its brushes. If this occurs during conversation and without a simultaneous advance of the brushes at the transmitter, the receiving circuit is momentarily disabled from receiving intelligible speech. However, upon the first pause in the conversation sufficiently long to advance the brushes at the transmitter, the two stations are again in step and conversation may proceed in the normal manner. In such a contingency the loss of a few syllables or words might occur, but in a two-way system such as would ordinarily be employed the speaker at the transmitter could readily be asked to repeat this lost portion of the sentence. It is evident that in case of such a lack of synchronism between the mechanisms of the two stations, the missed words through lack of synchronism would be heard as noise at the receiving station so that the receiving party would know that words were being spoken and that a lapse was not occurring in the speech.

In the very unlikely event of the transmitter brush arms taking one step without a corresponding advance of the receiver brush arms, it would be necessary for the transmitter brushes to take one less than the total number of additional steps necessary to advance a brush from any given position through all the positions and back into that position. The receiver brush arms would, of course, be forced to wait for the transmitter brush arms to come into corresponding position, since the energy necessary to move the receiver brushes is not received until the apparatus at both stations is in step.

No provision is shown in either of the described systems for carrying on two way conversation but it will be obvious that a return channel can be provided by a mere duplication of the apparatus shown with or without the use of different frequencies at the various points throughout the system.

Provision is shown in Figs. 9 and 10 for only a single false carrier or noise component but it will be obvious that a plurality of false carriers may be employed in the manner generally indicated in Figs.

7 and 8 and that by providing sufficient brush arms and filters at the various points in the circuit, the frequency of each of the false carriers or of one or more of them 5 may be shifted from time to time.

In the system described in Figs. 7 and 8 employing two false carriers or noise components, both side bands of the speech modulated wave are transmitted and one of 10 the noise components is inserted in each side band. It is within the invention, however, to supply a plurality of noise components to a single side band and to transmit only this side band, suppressing transmission of 15 both the unmodulated carrier and the opposite side band. It is also within the invention to transmit two false carriers and either a single side band or both side bands, whether the false carriers lie within the 20 limits of the side bands or outside these limits, and to introduce frequency shifts into one or more of the false carriers.

The foregoing descriptions assume that harmonics, as high as the sixteenth, are obtainable in the output of a harmonic generator but it will be obvious that the sixteenth harmonic or any desired harmonic of a wave may be secured by means of a 25 plurality of harmonic generators operating 30 in tandem with proper selecting circuits between, and accordingly, in case the desired harmonic is not obtainable from a single harmonic generator, it will be obvious to supply other harmonic generators 35 where they may be needed throughout the system.

It is to be understood that the scope of the invention is defined in the following 40 claims and that the invention is not to be construed as limited by the specific showing either in the drawing or the description, this being for illustrative purposes only and merely by way of example.

What is claimed is:

45 1. In signaling in which the signal is revealed at a receiving point by derivation from a carrier wave component and components containing signaling variations, the method of obtaining secrecy in transmission 50 comprising replacing the carrier wave component by a component of a different frequency, transmitting the wave so altered, and deriving at a receiving point the carrier component from the component of different 55 frequency.

2. The method of purposely reducing the degree of intelligibility of a modulated wave comprising suppressing the unmodulated carrier component of the modulated wave 60 and introducing a sustained wave of a frequency different from the carrier frequency by an amount between the audio frequency limits.

65 3. The method of secret transmission comprising modulating a carrier wave by speech,

suppressing the unmodulated carrier component from transmission and introducing into the modulated wave a sustained wave of such frequency as to produce in the resulting modulated wave a component of the order 70 of frequency of one of the speech side bands of the modulated wave.

4. The method of secret transmission comprising modulating a carrier wave by speech and by a confusion current of a definite frequency within the audible frequency range, and suppressing transmission of the unmodulated carrier component.

5. The method of secret transmission comprising producing waves of two bands of 80 frequencies, each band of a frequency width corresponding to essential speech frequency range and each representing the same speech, introducing in each of said bands a different character of distortion, and modulating 85 a carrier wave in accordance with both of the distorted bands.

6. The method of secret transmission comprising modulating a carrier wave by speech waves, and introducing into the modulated 90 wave sustained confusion components unsymmetrically related in frequency with respect to the carrier frequency and differing from the carrier frequency by an amount within the limits of speech frequencies.

7. The method of secret transmission comprising producing two bands of waves each 100 of speech frequency width and each representing the same speech, introducing into each of said waves a confusion component of respectively different frequency, and modulating a carrier wave by said waves.

8. The method of producing a speech-modulated carrier wave containing both side bands and confusion components, which 105 comprises modulating a relatively low-frequency wave by speech and a confusion component, selecting the upper side band of the wave so modulated, modulating said low-frequency wave by the same speech and a confusion component, selecting the lower side band of the wave so modulated, modulating a high-frequency wave by both of 110 said selected side bands, and selecting for transmission one of the side bands resulting 115 from the modulation of the high-frequency wave.

9. The method of secret transmission comprising modulating a sustained wave with the same speech waves by separate modulating operations, introducing into the modulated waves so produced respectively different distortions, selecting the upper side band of one of the modulated waves and the lower side band of the other modulated wave and transmitting said side bands together over the same medium.

10. The method of secret telephony comprising modulating a carrier wave by speech, suppressing transmission of the un- 120

modulated carrier component, introducing a confusion component into the modulated wave, the frequency of said confusion component lying within the frequency limits 5 occupied by one of the speech side bands of the modulated wave, deriving at a receiving station a wave of the carrier frequency from said confusion component and utilizing said derived wave to receive speech from said 10 modulated wave.

11. The method of secret telephony comprising modulating a carrier wave by speech, introducing into each of the two side bands of the speech-modulated wave a confusion component, obtaining at a receiving point the beat between said confusion components, and utilizing said beat to derive components for neutralizing the confusion components in the speech to be received.

12. Means to produce a wave for secret transmission of speech comprising means for modulating a carrier wave by speech and suppressing transmission of the unmodulated carrier frequency component, and means to 25 superpose the modulated wave upon a sustained wave of relatively large amplitude and of a frequency differing from the carrier frequency by an amount small enough to produce unintelligible audio waves when 30 detected.

13. Means to produce a wave for the secret transmission of speech comprising means for modulating a carrier wave by speech and suppressing transmission of the unmodulated carrier component, means to transmit the two speech side bands of the modulated wave, means to transmit with said modulated wave a sustained wave of the same order of frequency as the frequencies of one of the side bands and a sustained wave of a frequency lying to the other side of the carrier frequency and spaced in frequency from said carrier frequency by an 40 interval different from the interval between the carrier frequency and the frequency of any sustained wave component on the same side of the carrier frequency as the first mentioned sustained wave.

14. Means to produce a wave for the secret transmission of speech comprising means to produce an upper side band of a speech modulated wave of arbitrary frequency and to distort said upper side band wave, means to produce a lower side band wave by modulation of the same arbitrary frequency wave by the same speech waves, and to distort in a different manner said lower side band wave and means to modulate a carrier wave by both of said side band waves.

15. In secret signaling, means to modulate a carrier wave by speech and means to introduce into the modulated wave a plurality of confusion components of respective frequencies lying to each side of the carrier frequency and unsymmetrically positioned

in frequency with respect to the carrier frequency.

16. In secret telephony, means to modulate a wave of sustained frequency by speech, means to introduce into the upper side band 50 of the wave so modulated a confusion component of a frequency within the frequency limits of said side band, means to introduce into the lower side band a confusion component occupying a relatively different 55 position with respect to the frequency limits of that side band, and means to transmit said two side bands containing said confusion components over a common medium to the substantial exclusion of wave components of other frequencies.

17. In secret telephony means to modulate a wave of arbitrary frequency by speech, means to introduce into the upper side band 60 of the resulting modulated wave a confusion component of a frequency within the frequency limits of said side band, means to introduce into the lower side band a component of a frequency within the frequency limits of that side band, said latter component occupying a relatively different frequency location from the first component with respect to the said arbitrary frequency, means to select said two side bands and said 65 confusion components, and means to modulate a carrier wave thereby.

18. In a signaling system, means to modulate a carrier wave by speech and to suppress transmission of the unmodulated carrier component, means to introduce a confusion component into the modulated wave, and means at a receiving point to derive a wave of the carrier frequency from said 70 confusion component.

19. In a signaling system means to modulate a carrier wave by speech and to suppress transmission of the unmodulated carrier component leaving the two speech sidebands for transmission, means to introduce a confusion component of a frequency within 75 the frequency limits occupied by one side band and a confusion component within the frequency limits occupied by the other side band, and means at a receiving point for deriving from said confusion components a 80 wave of the carrier frequency and other components for neutralizing the effect upon received speech of said confusion components.

20. In a secret telephone system, means to modulate a carrier wave by speech waves and to introduce confusion components into the modulated wave, means at a receiving point to obtain the beat wave between said confusion components and to derive from 85 said beat wave components for neutralizing the effect on the received speech of said confusion components.

21. In a secret telephone system, means to modulate a carrier wave by speech and to 90

- suppress the unmodulated carrier component, means to introduce into the modulated wave a sustained false carrier component of a frequency differing from the suppressed carrier component by an amount within the limits of speech frequencies, and means to transmit the false carrier wave and the speech modulation components of the modulated wave.
- 10 22. In a secret telephone system means to produce speech modulation components of a carrier wave substantially free from components of the unmodulated carrier frequency, means to produce false carrier waves differing in frequency from said unmodulated carrier frequency, means to transmit said false carriers and said speech modulation components over the same medium, said false carriers being so related in frequency 15 to said modulation components as to permit of reception of only unintelligible sounds by ordinary detection, and means at a receiving point for deriving intelligible speech from said speech modulation components under 20 control of said false carrier waves.
23. In a secret telephone system, means to produce speech side bands of a true carrier wave and to superpose said side bands upon a false carrier wave for transmission, 25 said false carrier wave having such a frequency relative to said side bands as to permit of reception of only unintelligible sounds by mere detection of the transmitted waves, and means at a receiving point 30 for deriving a wave of the frequency of the true carrier from said false carrier wave and for utilizing said derived wave to receive intelligible speech from the received waves.
- 35 40 24. In a system of secret telephony, means to produce speech side bands of a true carrier wave and to superpose said side bands upon false carrier waves for transmission comprising a source of base frequency waves, a harmonic generator for deriving waves of intermediate frequencies from the waves from said source, means for deriving higher frequency waves from one of said intermediate frequency waves, 45 means to modulate an intermediate frequency wave by speech and by other intermediate frequency waves, means to select the modulation components resulting from such modulation and comprising speech 50 side band components and components representing modulation by intermediate frequency components, means to modulate said higher frequency waves by the selected modulation components, and means to select for transmission one side band of the 55 last resulting modulated wave.
- 60 65 25. In a secret telephone system, means to produce speech side bands of a carrier wave and to suppress transmission of the unmodulated carrier component, means to superpose said side bands upon a plurality of false carrier waves unsymmetrically positioned in frequency with respect to the frequency of the carrier wave by which said side bands were produced, means at a receiving point to produce combination frequency components of said false carrier waves, and means for employing said combination frequency components to reproduce a wave of the frequency of the suppressed carrier and to reproduce speech currents from the side band components, substantially free from effect of said false carrier components.
- 70 75 80 85 90 26. In secret telephony, means to produce speech side bands of a carrier wave and to suppress transmission of the unmodulated carrier component, means to superpose confusion currents upon said side bands and to transmit the side bands and confusion components together, means at a receiving point for deriving from the confusion components a wave of the carrier frequency and waves of frequencies equal to the frequencies of the confusion components, and means to combine the received waves with the derived waves to reproduce speech waves substantially free of the effects of said confusion components.
- 95 100 105 110 115 120 125 130 27. In secret telephony, means at a transmitting point to produce a sustained wave of a base frequency and to derive therefrom a carrier wave and confusion components, means to modulate the carrier wave by speech and said confusion components and to suppress transmission of the unmodulated carrier component, means to transmit the resulting modulation components to a distance, means at a receiving point for deriving from the modulation components produced by the confusion components a wave of the base frequency, means for producing from the derived wave a base frequency, a wave of the carrier frequency and waves of the frequencies of the respective confusion components, and means to combine the waves so produced with the received waves to reproduce speech waves substantially free of the effects of said confusion components.
- 115 120 125 130 28. In secret telephony, means to transmit a speech modulated carrier wave and confusion waves together, the confusion waves bearing such frequency relation with respect to the carrier frequency as to permit of reception of only unintelligible sounds by ordinary detection, means at a designated receiving point for combining the confusion components to reproduce waves of the frequencies of said confusion waves, and means to combine the reproduced waves with the received waves and thereby to neutralize the effect upon the intelligibility of the detected currents of said confusion waves.

29. In secret telephony, means to produce a speech modulated wave for transmission, means to superpose on said waves confusion waves, means at a receiving point to utilize said confusion waves to reproduce components for neutralizing the confusion waves to enable reception of intelligible speech, and means to change the frequency of the confusion waves during transmission of a speech message. 60
30. In secret telephony, means to transmit a speech modulated wave and to superpose confusion waves on the transmitted speech modulated waves, and means operating under control of speech currents for changing the character of the confusion waves. 65
31. In secret telephony, means to transmit a speech modulated wave and to superpose confusion waves on the transmitted waves, and means controlled in response to a pause in the conversation for changing the character of the confusion waves. 70
32. In secret telephony, a source of high frequency waves, sources of confusion waves of respectively different character, means for interchangeably transmitting confusion waves of different character, means to modulate the high frequency waves by conversation currents and means controlled by the conversation currents for determining the particular character of confusion waves being transmitted at any instant. 75
33. In secret telephony, a source of carrier frequency waves at a transmitting point, means to produce a plurality of confusion waves of respectively different character, means to modulate the carrier waves by speech and by selected ones of the confusion waves, means at a receiving point to reproduce from the confusion waves, waves of the respective character to neutralize said confusion waves in their effect upon speech reception, means to utilize the reproduced waves to derive intelligible speech from the received waves and means at both the transmitting point and the receiving point controlled by speech currents for selecting at any instant the character of confusion waves to be transmitted and the character of neutralizing waves to be utilized respectively. 80
34. In secret telephony means at a transmitting point to produce a wave of base frequency and to derive therefrom a carrier wave and confusion waves for transmission, means to change the character of the con- 85
- fusion waves from time to time, means at a receiving point to derive from the confusion waves of one character a wave of said base frequency and to reproduce therefrom a wave of the frequency of said carrier wave, and means to derive from the confusion waves of changed character at any instant a wave of the same base frequency. 90
35. In secret telephony, means to build up and transmit a composite wave comprising speech side bands of a modulated carrier wave and confusion waves for preventing reception of intelligible speech from the transmitted waves by ordinary detecting processes, means to change the character of the confusion currents from time to time under control of speech waves, means at a receiving point to reproduce from said composite wave waves of the character necessary to neutralize the effect of said confusion waves upon the reception of speech to enable intelligible speech to be received, and means controlled by the received speech currents for changing the character of the neutralizing waves in accordance with the change in character of said confusion waves at the transmitting point. 95
36. The method of transmission comprising producing at a transmitting point two side bands of a high frequency wave, each of said side bands being of speech frequency width, suppressing the unmodulated component of said high frequency wave, transmitting the two side bands to a receiving point and there utilizing said side bands to produce unmodulated waves and combining said unmodulated waves with the received side bands to produce speech waves. 100
37. In a carrier system, the method of transmitting signals, which comprises separately modulating a carrier wave by signals derived from a single source, selecting one side band of each modulation, and transmitting the selected side bands over a single channel. 105
38. A carrier system comprising means for separately modulating a carrier wave by signals derived from a single source, means for selecting one side band of one modulation, means for selecting one side band of the other modulation and means for simultaneously transmitting the selected side bands over a single channel. 110

In witness whereof, I hereunto subscribe my name this 22 day of June A. D., 1923.

JOSEPH W. HORTON.
